United States Patent Office.

A. S. DINSMORE, OF NEW YORK, N. Y.

Letters Patent No. 91,922, dated June 29, 1869.

IMPROVEMENT IN TUCKING-ATTACHMENT FOR SEWING-MACHINES.

The Schedule referred to in these Letters Patent and making part of the same.

To all whom it may concern:

Be it known that I, A. S. DINSMORE, of New York, in the county of New York, and State of New York, have invented a new and improved Tucker-Attachment for Sewing-Machines; and I do hereby declare that the following is a full, clear, and exact description thereof, which will enable others skilled in the art to make and use the same, reference being had to the accompanying drawings, forming part of this specification, in which—

Figure 1 is a side view of the forward part of the arm of a sewing-machine, shewing the tucker attached to its presser-foot.

Figure 2 is a side view of the tucker, showing it attached to the presser-foot.

Figure 3 is a detail perspective view of the tucker.

Similar letters of reference indicate corresponding parts.

My invention has for its object to furnish an improved tucker for sewing-machines, which shall be so constructed that it may be conveniently attached to and detached from the ordinary presser-foot of a sewing-machine, and which will enable narrow tucks to be conveniently and accurately formed; and

It consists in the tucker, constructed as hereinafter more fully described, in combination with the ordinary presser-foot of a sewing-machine.

A represents the forward part of the arm of a sewing-machine.

B represents the presser-foot, which is constructed and attached to the arm A, in the ordinary manner.

C is the tucker, which is a small rectangular plate, having a narrow rib formed upon its under side, along its inner edge, next to the gauge, so that the said rib may press upon and hold the fold of the cloth being sewed, while the other part of said tucker moves over

but does not bear on the folds already made, as shown in red in fig. 1.

The tucker C has two holes formed in it, one for the passage of the needle, and the other to receive the screw c, by means of which it is secured to the presser-foot B, said screw passing through a hole or slot in the said presser-foot B, as shown in fig. 2.

The tucker C must be attached to the presser-foot B, in such a position that the hole for the needle, in the said tucker C, may be directly beneath the hole for the needle in the presser-foot B, so that the needle may pass through both holes at the same time.

This construction enables the tucker to be easily and conveniently attached to and removed from the sewing-machine, without its being necessary to disturb the position of any of the other parts of the machine.

The rib is formed on that side of the tucker next the gauge, which is attached to the bed-plate of the machine, and the plait being laid, bears against said gauge when in operation.

Having thus described my invention,
I claim as new, and desire to secure by Letters Patent—

The tucking-attachment secured to the presser-foot, when constructed, as described, of the rectangular plate C, having the narrow rib formed upon its inner side, along its inner edge, through which the needle passes, whereby the rib is adapted to press upon and hold the fold of the cloth, while the remaining portion moves over the folds already formed, without bearing on it, as herein described, for the purpose specified.

The above specification of my invention signed by me, this 10th day of March, 1869.

Witnesses: A. S. DINSMORE.
